US00D481800S

(12) **United States Design Patent** (10) Patent No.: **US D481,800 S**
(45) Date of Patent: ** Nov. 4, 2003

(54) **TEST DEVICE**

(75) Inventors: **R. Sam Niedbala**, Allentown, PA (US);
John W. Scott, Perkasie, PA (US);
Peter A. Bourdelle, Allentown, PA
(US); **Hans H. Feindt**, Allentown, PA
(US)

(73) Assignee: **Orasure Technologies, Inc.**,
Bethlehem, PA (US)

(**) Term: **14 Years**

(21) Appl. No.: **29/176,072**

(22) Filed: **Feb. 19, 2003**
